UNITED STATES PATENT OFFICE.

SOLOMON M. EISEMAN, OF NEW YORK, N. Y.

IMPROVEMENT IN CLOTH-CUTTING MACHINES.

Specification forming part of Letters Patent No. 129,939, dated July 30, 1872.

Specification describing a new and useful Improvement in Cloth-Cutting Machines, invented by SOLOMON MAYER EISEMAN, of the city, county, and State of New York.

Figure 1 is a rear view of my improved machine, part being broken away to show the construction. Fig. 2 is a side view of the same, partly in section, through the line α α , Fig. 1. Fig. 3 is a top view of the knife-plate. Fig. 4 is a face view of the knife-plate.

Similar letters of reference indicate corresponding parts.

My invention has for its object to furnish an improved machine for cutting cloth, paper, woven or felted fabrics, metals, and substances of all kinds formed in sheets, into any desired form. The cutting-knives are operated by means of a gravitating cutter-head so arranged and constructed that, by the fall of the cutter-head and knives, several thicknesses or sheets of the material may be simultaneously cut.

The construction and arrangement of the parts or devices composing the machine and constituting the novelty claimed are as follows: A are uprights, two or more of which may be used, and which are connected at their lower end by a platform, B, to which the bed-plate C is attached. At their upper ends the uprights are connected by the cross-bar D. E is the cutter-head or drop-plate, which is attached to the slides F that move up and down in ways upon the inner sides of the posts or uprights A. To the center of the drop-plate E is attached one end of the rope G, which passes up through a hole in the center of the cross-bar D, over the pulley H, and down into such a position that it may be conveniently operated by the operator with his hand or foot or by other power. The pulley H is pivoted to and between two brackets or studs, I, attached to the cross-bar D in such position that the face of the pulley upon one side may be directly over the hole in the cross-bar D through which the rope G passes. To the lower face of the plate E may be secured, by screws or bolts, a plate, J, which is slotted in the manner shown in Figs. 3 and 4, to receive the screws or bolts K, and the upper side of which is recessed, as shown in Fig. 3, to furnish space for the heads of the said bolts K. L are studs,

the bases of which are slotted to receive the bolts K, by which they are secured to the plate J, and their projecting ends are slotted to receive the knives or cutters M, which may be secured in place by set-screws or other conveniently-detachable means. The knives or cutters M are made of spring-steel or other elastic material, so that they may take any desired curve.

In using the machine the pattern of the piece to be cut is drawn upon the face of the plate, or is attached temporarily to said plate. Knives of the proper length are then adjusted to the pattern by adjusting the studs L and bolts K, as many studs L being used as may be required to bring the knives M to and hold them in the proper shape. The plate J and its attached knives are then secured to the plate E, a plate of rubber being interposed between the said plates J and E, and the drop is raised by means of the rope G or other suitable means, and secured by a hook, N, or other suitable device. The desired number of sheets of cloth, paper, or other material, according to the weight of the drop, are then arranged upon the plate C. The plate J and its attached knives, instead of being secured to the plate E, may be laid upon the material to be cut. The drop may then be allowed to fall, cutting all the thicknesses of the material.

This machine is particularly useful for tailors in cutting out clothes, as it permits the cutting of many thicknesses of cloth at a time with the utmost exactness. My improvement may also be used with equal facility and advantage for paper-cutting, metal-cutting, and various other purposes.

In the foregoing description I have described the use of a gravitating cutter head or drop, to which the flexible knives are attached; but it will be readily understood that, instead of a drop, the power necessary to force the knives through the material may be obtained by using screws or levers suitably applied upon the back of the plate to which the flexible knives are attached. I, however, prefer the use of the drop, as set forth.

I do not limit or confine myself to the exact form or arrangement of any of the parts herein described, as that may be varied in many ways without departing from my improvement

Having thus described my invention, I claim as new and desire to secure by Letters Patent—

1. The slotted studs L and bolts K, in combination with the knives M and slotted plate J, all constructed as shown and described, to permit of adjustment in the manner specified.

2. In combination with flexible knives, I claim the slotted plates J, upon which the said knives are set and held, substantially as herein described.

3. The combination of the frame A, B, D, bed-plate C, drop-plate E, slide F, knife-plate J, bolts K, studs L, and knives M with each other, substantially as herein shown and described, and for the purpose set forth.

SOLOMON MAYER EISEMAN.
